UNITED STATES PATENT OFFICE.

ANDREW P. STULTS, OF ZANESVILLE, OHIO.

DESIGN FOR A GRAVE-MARKER.

No. 40,017.

Specification for Design.

Patented May 25, 1909.

Application filed January 20, 1909. Serial No. 473,384. Term of patent 7 years.

To all whom it may concern:

Be it known that I, ANDREW P. STULTS, a citizen of the United States, residing at Zanesville, in the county of Muskingum and State of Ohio, have invented a new, original, and ornamental Design for a Grave-Marker, of which the following is a specification, reference being had to the accompanying drawing, forming part thereof.

Figure 1 is a view in side elevation of a

grave marker, showing my new design, and Fig. 2 is a perspective view of the grave marker.

I claim:—

The ornamental design for a grave marker as shown.

ANDREW P. STULTS.
